RECTIFYING APPARATUS

Peter Peff, West Orange, N. J.

Application March 22, 1938, Serial No. 197,427

5 Claims. (Cl. 261—114)

This invention relates to improvements in rectifying apparatus; and the invention has reference, more particularly, to improvements in rectifying columns adapted to be employed, among 5 other uses, for the separation of the various gaseous constituents of atmospheric gas mixtures, such e. g. as oxygen, nitrogen, argon and neon gases.

This invention has for an object to provide a 10 novel construction and relative arrangement of bubble cap trays for rectifying columns; and the invention has for a further object to provide a novel construction of bubble cap means per se, for use in connection with such trays.

15 Other objects of this invention, not at this time more particularly enumerated, will be understood from the following detailed description of the same.

An illustrative embodiment of this invention 20 is shown in the accompanying drawing, in which:

Fig. 1 is a vertical longitudinal sectional view of a plurality of bubble cap trays according to this invention, and as arranged in operative assembled relation; Fig. 2 is a plan view of one of said 25 trays; Fig. 3 is a side elevation of a novel bubble cap structure with which the trays are provided, the same being drawn on a scale greatly in excess of actual size; Fig. 4 is a vertical longitudinal sectional view of the novel bubble cap structure; 30 and Fig. 5 is a horizontal sectional view thereof, taken on line 5—5 in Fig. 4.

Similar characters of reference are employed in the above described views, to indicate corresponding parts.

35 The novel rectifying apparatus according to this invention, comprises a multiplicity of horizontal trays superimposed one upon another to form a column, and so constructed and related that condensed liquid or reflux, produced in the 40 operation of the column, will overflow from the trays so as to descend through the column from one tray to another. Each tray is provided with a multiplicity of bubble cap structures through which gases may rise in ascending the column 45 from tray to tray.

In preferred form each tray comprises a peripheral and preferably annular side wall member 10 of suitable height to provide a desired gas chamber capacity between adjacent assembled 50 trays. At one end, preferably the upper end, a marginal portion of said side wall member 10 is laterally offset to provide a receiving collar 11 and seat 12 to telescopically receive the adjoining end of a superimposed tray, whereby the trays 55 forming the column are successively connected

one with another. Suitably secured to the side wall member 10, intermediate the upper and lower margins thereof and so as to extend horizontally across the area bounded thereby, is a tray bottom plate 13. The tray bottom plate 13 5 is cut away at one side along a chord or line intersecting the line of the side wall member 10 to form a spillway space 14 for communication with the next tray below. Disposed to extend vertically through this space 14 is a conduit 10 member 15 which is shaped in cross-section to conform thereto. The upper marginal portion of the inner vertical wall member of said conduit member 15, contiguous to the margin of the tray bottom plate 13, projects upwardly above 15 the level of the latter to thereby form a dam 16 of a height predetermined to correspond to a predetermined depth of reflux desired to be maintained in the tray. The extent of downward projection of the lower end of said conduit 20 member 15 is such, that its lower extremity will dip below the reflux level in the tray next below, thereby providing a liquid seal against passage of gases through said conduit member 15 from the gas chamber 17 intermediate said adjacent 25 trays. When assembling the trays one upon another, the conduit members 15 of alternate successive trays are oppositely disposed so that proper downward flow of reflux will be maintained from tray to tray. In order to assure a 30 properly sustained flow movement of reflux liquid as uniformly and widely distributed over the entire area of the tray bottom plate as possible, the external of the line of the dam 16 is desirably considerably in excess of the radius of the tray, 35 and e. g. is preferably of an extent of about one and one-half times the radius of the tray more or less.

Mounted in connection with each tray bottom plate 13 are a multiplicity of bubble cap devices 40 of novel construction. Each bubble cap device comprises a hollow cap shell 18 of desired cross-sectional shape, but preferably circular whereby said shell is cylindrical in form. Said cap shell 18 is open at its lower end, but is provided with a 45 top end wall 19 to close its upper end. Integrally formed with said top end wall 19 is a downwardly open hollow or recessed head 20 of reduced diameter. Said head 20 is aligned with the vertical axis of the shell 18 so as to be concentric to 50 the latter. Extending axially upward through the interior of said shell 18 is a cylindrical riser member or tube 21, the upper end of which is telescopically received into the internal recess of said head 20 so as to be closed thereby. Said 55

riser member 21 and shell 18 may be secured together in the described assembled relation in any suitable manner, as e. g. by interlocking tins 22 punched or struck out from the contiguous 5 side walls of said riser member 21 and head 20. The lower open end of the riser member 21 projects beyond the lower end of the shell 18. To assemble the bubble cap device in operative connection with and in upstanding relation to a 10 tray bottom plate 13, the projecting lower open end portion of the riser member 21 is inserted downwardly through a correspondingly sized opening 23 provided in the tray bottom plate until the bottom margin of the cap shell 18 abuts 15 and is stopped against the upper surface of said tray bottom plate, whereupon the bottom marginal portion of said riser member 21 is laterally and outwardly curled or flared over the under side of said tray bottom plate to form a retaining lip or bead 24 for anchoring the bubble cap device to the tray bottom plate. When the bubble cap device is thus assembled and mounted, the lower open end of the riser member 21 will communicate with the gas chamber 17 beneath the 20 tray bottom plate. It will be obvious that the riser member 21, as assembled with the cap shell 18 in the manner above described, will be immovably connected to the latter in concentric relation thereto so as to provide a uniform annular gas passage 25 between the cap shell and 25 riser member walls.

Formed in the wall of the riser member 21, immediately below the top end wall 19 of the cap shell 18 is a circumferential row of gas venting 30 ports 26 which open outwardly from the riser member interior into the annular gas passage 25 intermediate the riser member and cap shell. As thus positioned, these ports 26 are located above the level of reflux liquid contained within the 40 tray. Preferably said ports 26 are in the form of elongated closely spaced narrow slots.

Formed in the wall of the cap shell 18, adjacent to the bottom end thereof, is a circumferential row of gas escape ports 27 which open outwardly 45 from the annular gas passage 25 within the cap shell. These gas escape ports 27 are located below the level of reflux liquid contained within the tray, and are thus submerged in said liquid. Said gas escape ports 27 are also preferably in the form 50 of elongated closely spaced narrow slots, and terminate at their upper ends in inverted V-shaped or pointed end portions 28. The V-shaped or pointed formation of said end portions 28 of the gas escape ports 27 facilitate the breaking away 55 and upward flight through the reflux liquid of the bubbles of gas discharged through said ports. Preferably the length or height of the slot-like gas venting ports 26 and the gas escape ports 27 should approximate one-half the internal diameter 60 of the riser member 21.

For best results in the operation of the column for the rectification of atmospheric gas mixtures, a proper flow of velocity reflux liquid across the tray is facilitated by assembling the bubble cap devices to the tray bottom plates in staggered rows and in such spaced relation one to another that the clearance space therebetween approximates about one-quarter of the diameter of the caps.

70 The novel bubble cap structure, as above described is of high efficiency by reason of the fact that it functions to thoroughly break up the ascending gaseous vapors in such manner as to assure intimate contact of finely divided bubbles thereof with the liquid flowing across the trays.

By reason of the provision of the plurality of narrow gas venting ports 26 at the top of the riser 21, gaseous vapor, as they rise from a gas chamber 17 below the tray and pass upwardly through the riser, are deflected at the top of the riser through said venting ports 26 into the gas passage 25 of the cap shell. Such movement of the gaseous vapors through said venting ports 26 not only provides an initial breaking up of the vapors, but also tends to precipitate or separate from the vapors any droplets of condensate carried along therewith. As the initially broken up gaseous vapor enters and descends within the gas passage 25 of the cap shell, it is thereupon caused to next pass through the escape ports 27, whereby it is further broken up and brought into intimate contact with the reflux liquid flowing across the tray, the fine bubbles, as discharged rising through said reflux and discharging into the gas chamber 17 above the tray.

Owing to the interfitting relation of the riser member 21 and cap shell 18, a symmetrical, strong and durable bubble cap structure is provided, as well as one which may, by a simple mechanical operation, be strongly and rigidly anchored to the 25 tray bottom, so as to be firmly held against displacement from operative assembled relation to the latter.

Having now described my invention, I claim:

1. In a bubble cap tray for rectifying columns, 30 a bubble cap structure therefor comprising, a hollow cap shell closed at its upper end, a riser member of reduced diameter extending axially of said cap shell and having a portion of its upper end extending through the top end wall of 35 said cap shell and secured thereto thus providing an intermediate gas passage within said cap shell, the lower end portion of said riser member projecting downwardly through the bottom end of said cap shell and being adapted to extend 40 through a receiving opening provided in the tray bottom therefor and secured to thus anchor the bubble cap structure to the tray, said riser member having a plurality of gas vent ports opening into the upper end of said gas passage, and said 45 cap shell having a plurality of gas escape ports opening out of the lower end of said gas passage.

2. In a bubble cap tray for rectifying columns, 50 a bubble cap structure therefor comprising, a hollow cap shell closed at its upper end and provided with at such end with a centrally located upwardly offset recessed head of reduced diameter, a riser tube having its upper end fitted into and secured to said recessed head to extend axially downward through the interior of said cap shell, thereby forming an intermediate gas passage, the lower end portion of said riser tube projecting downwardly beyond the bottom end of 55 said cap shell and being adapted to extend through a receiving opening provided in the tray bottom therefor and secured to thus anchor the bubble cap structure to the tray, said riser tube having a plurality of gas vent ports in its upper end portion for communication with said intermediate gas passage, and said cap shell having a 60 plurality of gas escape ports in its lower end portion to open into the reflux liquid contained in the tray in use.

3. In a bubble cap structure as defined in claim 2, wherein said gas vent ports and said gas escape 70 ports each comprise rows of vertically extending slot-like openings, the length of said slots approximating about one-half the diameter of the riser tube.

4. In a bubble cap structure as defined in claim

2, wherein said gas vent ports and said gas escape ports each comprise rows of vertically extending slot-like openings, the length of said slots approximating about one-half the diameter of the 5 riser tube, and wherein the slots forming said gas escape ports terminate at their upper ends in inverted V-shaped extremities.

5. In a bubble cap structure as defined in claim 2, wherein the gas escape ports of said cap shell comprise a row of vertically extending slot-like openings, the length of said openings approximating about one-half the reflux depth capacity 5 of the tray.

PETER PEFF.
